GLUING-MACHINE.

1,196,026.

Specification of Letters Patent. Patented Aug. 29, 1916.

Application filed May 17, 1915. Serial No. 23,812.

To all whom it may concern:

Be it known that we, JAMES D. REIFSNYDER and HARRY B. SMITH, citizens of the United States, residing at Olney, Philadelphia, and Brooklyn, respectively, in the counties of Philadelphia and Kings, respectively, and States of Pennsylvania and New York, respectively, have invented new and useful Improvements in Gluing-Machines, 10 of which the following is a specification.

This invention relates to a machine for applying a substance such as an adhesive to a sheet or blank and particularly to that type of such machines in which the glue is 15 applied to the sheet or blank by the peripheral faces of rolls.

Although many features of this invention may be applied to gluing machines of different kinds, the invention by way of illustration 20 is described herein as applied to a machine which operates to apply two thin coats of a substance such as glue to the sheet or blank which is to be coated. It has been observed that for some classes of work a 25 more satisfactory coating of the blank results from this manner of coating it, namely, applying several thin coats instead of one thick coat.

A principal object of the invention is to 30 produce a machine operating to apply a plurality of coats of a substance to a blank or sheet, and to provide improved means for regulating the operation of the glue-applying rolls and particularly for regulating the 35 amount of the substance such as an adhesive which is applied by the rolls to the blank.

A further object of the invention is to provide a machine in which the arrangement 40 of the rolls greatly facilitates the guiding of the blank through the machine.

A further object of the invention is to provide an improved arrangement of rolls rendering the machine capable of coating 45 the entire surface of the blank with the substance or glue.

A further object of the invention is to produce a machine of this type in which the rolls can be very readily dismounted from the machine.

50 A further object of the invention is to produce a gluing machine having a feeding mechanism particularly facilitating the feeding of the blanks into the machine.

Further objects of the invention will appear more fully hereinafter.

The invention consists in the general combination of parts and details, all of which contribute to produce an efficient gluing machine.

A preferred embodiment of the invention 60 is set forth in the accompanying specification while the broad scope of the invention is set forth in the appended claims.

In the drawing, Figure 1 is a vertical section through a gluing machine and its feeding mechanism, certain parts being broken away. Fig. 2 is a plan of the parts shown in Fig. 1, certain parts being broken away. Fig. 3 is an end elevation of the gluing machine, certain parts being broken away and 70 particularly illustrating the means for effecting the adjustment of the glue-applying rolls. Fig. 4 is a developed plan illustrating an arrangement of the glue-applying rolls which we may adopt.

Referring more particularly to the parts, 10 represents the frame of the machine which may be of any suitable construction, preferably supporting a tank 11 for a substance such as glue which is to be applied to 80 the blanks. The upper portion of this frame 10 above the tank 11 preferably supports rotatably a distributor roll 12 which is preferably provided with a covering 13 of elastic material, such as rubber. When the machine 85 is in operation the shaft 14 of this roll is continuously driven. As the distributor roll 12 rotates, the glue is conveyed to it by a walloper or glue roller 15, the under surface of which is constantly in contact with 90 the bath of glue in the tank.

The gluing machine comprises two or three members each with separated glue-applying faces, arranged so that the glue-applying faces of one member are out of line 95 with the glue-applying faces of the other member or members. The blank moves past these members and they coöperate so as to completely cover it and may, if desired, apply more than one coat. These glue-applying 100 members are preferably in the form of rolls, A, B, C, and D, and the glue-applying members are arranged so that one member assists in guiding the blank off of the member in advance of it.

The frame 10 preferably comprises two

separated standards 16 and 17 for supporting the glue-applying rolls A, B, C, and D. These glue-applying rolls are preferably arranged so that one or more applications of the substance or glue from the tank will be made by them to a blank passing through the machine. Furthermore, they are all preferably supported so that they tend to gravitate toward the distributor roll and so that they are freely movable toward the roll or away from it. We also prefer to provide means for nicely regulating or adjusting the position of the glue-applying rolls with respect to the distributor roll so as to regulate the distance of the glue-applying faces of the rolls from that of the distributor roll. In this way the faces of the rolls may be made to nearly contact without pressing each other and a very nice regulation is obtained for the coating of glue which is conveyed from the distributor roll to the glue-applying rolls. In order to accomplish this, we prefer to arrange the glue-applying rolls in pairs such as the pair A and B. These rolls are preferably formed with separated glue-applying faces 19^a and 19^b, the former being on the roll A and the latter on the roll B. These glue-applying faces are arranged out of alinement with each other and the rolls are arranged relatively close together with the collars of one roll intermediate the collars of the other roll so that the glue-applying faces of one roll extend beyond the glue-applying faces of the other roll of that pair, that is, if the rolls are viewed in end elevation, their peripheries apparently intersect.

Beyond the rolls A and B are provided means for completing the coating operation which is commenced at these rolls. This means operates to coat any spaces left uncoated by the rolls and may apply a second coat over part of the area of the blank. For this purpose, in the present embodiment, in addition to the rolls A and B, we have illustrated two other rolls C and D which form a coöperating pair. These rolls are similarly constructed and similarly arranged to the rolls A and B. There may be as many of these different pairs of rolls as desired. Each pair of rolls coats any uncovered gap left by the other rolls, and preferably substantially coats the entire surface of the blank.

The rolls C and D are arranged with their glue-applying peripheral faces 19^c and 19^d out of alinement with the glue-applying peripheral faces of the rolls A and B. This arrangement is preferable because it insures the complete application of the glue to the blank. The desirability of this arrangement appears very clearly from a reference to Fig. 4, in which the glue-applying faces are represented as being the peripheral faces of collars 20, formed integrally on the rolls.

By arranging the rolls C and D so that they do not aline with the other rolls, the glue-applying faces 19^c of the roll C are in a position to apply a coating of glue along the lines of the adjacent edges of the glue-applying faces 19^a and 19^b. In this way, the second pair of rolls is made to apply a second coat and applies that coat in proper position to fill up any gaps which may possibly be left by the first pair of rolls. In order to support the rolls the standards 16 and 17 are preferably provided with open sockets 21 and these sockets receive and guide the ends of the shafts 22 of the glue-applying rolls. The glue-applying rolls are all preferably positively driven and this may be accomplished by means of a long-faced gear wheel 23 on the shaft 14 (see Fig. 2) and meshing with pinions 24 rigid with the shafts or gudgeons 22, and the ends of the shafts of these rolls simply rest freely in the sockets (see Fig. 3). It is evident from an inspection of Fig. 3 that the pinions 24 would interfere with each other unless they were arranged out of alinement with each other, as indicated in Fig. 2. We prefer to provide means for simultaneously adjusting all of these rolls A, B, C and D. For this purpose we prefer to provide a cam 25 which is adjustably supported on the axis of the shaft 14, and this cam has a plurality of cam edges 26 which engage respectively with the shafts or gudgeons 22 of the different rolls. This cam is duplicated at the other end of the machine and evidently by rotating these cams in one direction, the rolls could all be adjusted inwardly, whereas if the cam rotated in the opposite direction, the rolls would all be adjusted outwardly. Each of these cams 25 has a wing with a slot 25^a which receives a clamping stud 25^b secured in the frame. By means of these bolts the cams can be clamped in any adjusted position desired. All the glue-applying rolls, however, constantly tend to gravitate toward the distributor roll and so that their glue-applying faces tend to come into contact with the peripheral face of the distributor roll.

Between the rolls A and B, we prefer to provide means for coöperating with the rolls to assist in guiding the blank through the machine. This guiding means is preferably in the form of a small presser roller 27. This roller preferably has a plurality of equidistant circumferential ribs 28, and at each end of the roller enlargements or heads 29 are formed which roll on and are supported on corresponding enlargements or heads 30 on the rolls A and B (see Fig. 2). This arrangement operates to hold the presser roller at a suitable distance from the glue-applying faces of the rolls A and B, that is, so that the peripheries of the ribs 28 lie very near but do not touch the glue-ap-

plying faces. We prefer to adopt a similar arrangement for guiding the blank as it passes from the roll C to the roll D, and this guiding means preferably comprises a 5 presser roller 31; the details of the construction and arrangement of this roller 31 are the same as those just described in connection with the other presser roller.

Between the rollers B and C, we prefer 10 to provide a presser roller E which is of relatively large diameter and of considerable weight, and the ends of this roller are provided with circular heads or wheels 32 which roll upon the coöperating heads 30 on the 15 ends of the rolls B and C, and this operates to impart the weight of the roll E to the rolls B and C, at the same time holding the circumferential ribs 33 of this roller out of contact with but adjacent to the peripheral 20 faces of the rolls B and C. In order to coöperate with this roll E, we prefer to provide a plurality of guide fingers 34 which may, if desired, be attached in common to a bar 35. These fingers are preferably of 25 substantial U-form, the bend of the U being disposed toward the roll B from which the blank is received, and the free legs of the U projecting toward the roll C, and in such a way that they will operate to strip the blank 30 off of the glue-applying surface of the roll B and direct it against the surface of the roll C. For this purpose, the forward ends of the guide fingers 34 preferably project inwardly beyond the periphery of the roll 35 B. Similar guide fingers 36 are provided for taking the blank off of the surface of the last roll D and these fingers 36 direct the coated blank onto the upper run of an endless conveyer 37 which conveyer is 40 supported on a conveyer frame 38 which extends out over the tank 11. This conveyer preferably consists of a plurality of belts 37^a guided around suitable pulleys 39 and 40 supported on this frame. The frame 45 38 is preferably supported on the frame 10 on a suitable pivot 41, enabling it to be swung up when desired. The pulleys 39 are carried on a common shaft 42 driven continuously when the machine is in operation 50 by means of a gear 43 at its end, actuated by gears 44 and 45, the latter of which meshes with the aforesaid gear 23. We provide means to prevent the coated blanks from curling up at their edges. Above the 55 belts 37^a a plurality of narrower belts 46 are provided which are to keep the glue-coated blank from curling up. These belts run substantially parallel with and near the belts 37^a, their lower ends passing around 60 pulleys 47 on a common shaft 48, and this shaft 48 is driven continuously by a gear 49 on shaft 42 which meshes with the gear 50 on the shaft 48. While the coated blanks are lying on the conveyer 37 they have their 65 glued side down. As each blank passes

around the pulleys 40, it is stripped off the belts 37^a by suitable guides 51 (see Fig. 1) and each blank then falls down onto an inclined shelf or delivery table 52.

When the gluing machine is in operation, 70 it is usually run in conjunction with another machine such as a wrapping machine which is being fed with the glued wrappers. The operator of such machine constantly removes each glued blank as it arrives at the 75 table 52. The wrapping machine and the gluing machine are both controlled by the operator of the wrapping machine so that when the wrapping machine stops, the gluing machine also stops and this arrangement 80 prevents any possibility of two or more wrappers arriving on the delivery shelf 52 at the same time and so that they could become stuck together. If necessary, the belts 46 may have a special form particularly adapting them to their purpose. For instance, we 85 may employ coiled wire belts, the coils of which tend to prevent the curling edges from slipping by when they are trying to curl. 90

The wallower roller 15 is preferably hung on its gudgeons 57 between two arms 54 and these arms are mounted to swing on rotating pivot pins 55 at the sides of the tank, and are adjustable on said pivots by means 95 of adjusting screws 56. The gudgeons 57 of the roller 15 are about on a line between the pivots 55 and the shaft 14 so that by swinging the arms 54 upwardly the roller 15 can be swung out of the tank and also 100 out of engagement with the distributor roll 13 which conveys the glue from the wallower 15 to the glue-applying rolls. By swinging the frame 38 upwardly, the rolls C and D as well as their adjacent roll 31 105 will be exposed so that they can be readily removed from their bearings, if desired.

The sheets or blanks 58 which are to be coated with glue are preferably supported in a pack 59 with the sheets 58 on edge (see 110 Fig. 1). The mechanism for supporting this pack and for oscillating the pack so as to present the foremost sheet to the glue-applying roll A is covered in Patent No. 1,152,358 dated August 31, 1915. This feeding mechanism will now be briefly described: 115 It comprises an inclined table 60 which is provided with a rack 61 which is reciprocated by means of a cam 62 on a cam shaft 63. The cam operates a rock lever 64, the short end of which is connected at 65 with the rack 61. A spring 66 tends to pull the rack outwardly on the table and in a direction to hold the roller 67 of the lever 64 against the cam 62. The connection at 65 is a pin and slot connection. Back of the pack 59 there is mounted a follower or pusher 68 preferably comprising a base or slide 69 mounted to travel inwardly along the table. On the base 69, is pivoted a gear 120 125

wheel 70 and a pawl carrier 71, said pawl carrier having a pawl 72 which engages the teeth of the gear wheel 70. As the rack 61 moves in an outward direction on the table, it moves the gear wheel 70 in a right hand direction and through the medium of the pawl 72 it rocks the pawl carrier 71 and this pawl carrier oscillates a pusher plate 73 which is pivotally mounted at 74 on the base 69, the said pawl carrier being connected by a link 75 with this plate. In the normal operation of the machine, this plate 73 simply oscillates on its pivot 74. If the forward oscillation of the plate should be excessive such as that indicated in Fig. 1, the end of the pawl 72 comes out of engagement with a latch 76 and then frees itself automatically from the teeth due to the special construction of the nose 77 of this pawl. When this occurs the plate 73 falls back toward the left, as viewed in Fig. 1 and the pawl 72 gets a new engagement with the teeth of the gear. As the pawl 72 moves back with the plate 73, it engages the shoulder 78 of the latch 76 and pushes this latch back against the resistance of its spring 79, and the latch is then moved back into its normal position by its spring, pushing the pawl 72 into engagement with the teeth of the gear wheel. In this way the pawl automatically takes a new grip on the gear wheel if the plate 73 has an excessive forward oscillation. In addition to this there is provided a detent pawl 80 which is mounted on the base and pressed into engagement with the teeth of the gear wheel by a spring 81. If such an excessive movement of the oscillating plate 73 occurs, such as just described, a tooth of the gear wheel 70 will move past the pawl 80 and the pawl will prevent the gear wheel from returning when the rack 61 moves upwardly. Therefore, this upward movement of the rack will pull the gear wheel 70 and the base 69 upwardly on the inclined table. In order to prevent the pusher from slipping back on the inclined table and for holding the ground gained in the upward movement given to it by the rack, we provide a ratchet rack 82 with inclined teeth and we also provide a pawl 83 which meshes with these teeth and prevents the base from slipping back. This pawl is pressed into engagement with the ratchet rack by a suitable spring 84. The rack 61 is suitably guided by pin and slot connections 85 on the under side of the table.

In order to adjust the height of the pack with relation to the roll A, we prefer to provide a manually operated adjusting screw 86 which passes through a threaded sleeve or nut 87 attached to the table 60. In order to maintain the engagement with the cam 62 on the shaft 63, the cam 62 is arranged to slide along on the shaft 63

through the medium of a feather running 65 in a slot 87 in the cam shaft. An adjustable stop 88 is provided for limiting the forward movement of the pawl carrier 71.

In order to effect a uniform distribution of the glue on the distributor roll 13, we prefer to constantly shift that roll longitudinally to and fro on the wallower 15. In order to accomplish this movement in a simple manner, we prefer to provide a gear cam 89, the rim of which is warped out of 70 its proper plane and thus constitutes a cam (see Fig. 2) so that the edges of the rim operate upon a grooved roller 90 fixed to shaft 14, and shift the shaft longitudinally in its bearings. At the same time the gear teeth on the rim 89 mesh with corresponding gear teeth 91 at the bottom of the grooved roller 90 so that this cam gear not only affords means for shifting the shaft 14, but also affords means for rotating it. By reason of the long face or gear 23 driving engagement is maintained with the pinions 24.

In order to support and guide a pack 59 of the sheets on one edge, we prefer to provide a guide rod 92 which is suitably supported in an adjustable bracket 93 on the table, and this guide rod passes through a suitable slot 94 in the oscillating plate 73. The cam shaft 63 is preferably continuously driven by a shaft 95 which actuates 95 it through suitable bevel gears 96.

When the gluing machine is in operation, the starting of the wrapping machine by the operator starts the gluing machine and also starts the feed movement from the pack 100 59. The plate 73 oscillates toward the gluing machine and moves the upper portion of the pack over toward it so that the upper edge of the foremost blank is pressed against the glue-applying roll A. Then the 105 plate 73 oscillates away from the pack and relieves the foremost blank of any pressure from the pack. The foremost sheet adheres to the roll A and rolls up on it so that the upper edge of the foremost blank 110 or sheet passes under the guide roll 27 and is then guided on through the machine so that the blank will pass on through the machine and between the belts 37 and 46.

It is understood that the embodiment of 115 the invention set forth herein is only one of the many embodiments or forms the invention may take, and we do not wish to be limited in the practice of the invention nor in our claims to the particular embodiment 120 set forth.

What we claim is:

1. A machine for completely coating one surface of a blank with an adhesive, comprising a member having a plurality of 125 separated adhesive applying faces and a second member having a plurality of separated adhesive applying faces operating to

guide the blank from said first named faces, and means for effecting a movement of the blank past said members in succession.

2. A machine for completely coating one surface of a blank with an adhesive, comprising a member having a plurality of separated adhesive applying faces and a second member having a plurality of separated adhesive applying faces operating to 10 guide the blank from said first named faces, and another member having a plurality of adhesive applying faces substantially out of alinement with the faces of both of said first named members.
- 15 3. A machine for completely coating one surface of a blank with an adhesive, comprising a pair of rolls with glue-applying faces, said rolls arranged so that the periphery of one of said rolls projects beyond 20 the periphery of the other of said rolls, whereby one of said rolls guides the blank from the other roll when said rolls are rotated.

4. A machine for completely coating one surface of a blank with an adhesive, comprising a pair of rolls each having collars with peripheral faces for applying the adhesive, the collars of one of said rolls disposed intermediate of the collars of the other 30 of said rolls and means for supplying adhesive to said pair of rolls.

5. A machine for completely coating one surface of a blank with an adhesive, comprising a pair of rolls having collars with 35 peripheral faces for applying the adhesive, the collars of one of said rolls disposed intermediate of the collars of the other of said rolls, and another roll having adhesive applying faces out of alinement with the 40 said peripheral faces of said collars for applying an adhesive to the blank.

6. A machine for completely coating one surface of a blank with an adhesive, comprising a pair of rolls having collars with 45 peripheral faces for applying the adhesive, the collars of one of said rolls disposed intermediate of the collars of the other of said rolls, and a distributor roll for conveying the adhesive to the peripheral faces of said 50 pair of rolls.

7. A machine for completely coating one surface of a blank with an adhesive, comprising a pair of rolls with glue-applying faces, said rolls arranged so that the periphery of one of said rolls projects beyond the periphery of the other of said rolls, whereby one of said rolls guides the blank from the other roll when said rolls are rotating, and a second pair of rolls having glue-applying 55 faces, said second pair of rolls arranged so that the periphery of one of said rolls projects beyond the periphery of the other of said rolls, the glue-applying faces of said second pair of rolls being out of alinement

of the glue-applying faces of said first 65 named rolls.

8. A machine for completely coating one surface of a blank with an adhesive, comprising a pair of rolls with glue-applying faces, said rolls arranged so that the periphery of one of said rolls projects beyond the periphery of the other of said rolls, whereby one of said rolls guides the blank from the other roll when said rolls are rotating, and a second pair of rolls having glue-applying faces, said second pair of rolls arranged so that the periphery of one of said rolls projects beyond the periphery of the other of said rolls, the glue-applying faces of said second pair of rolls being out of 70 alinement of the glue-applying faces of said first named rolls, and a guide roller between said first pair of rolls and said second pair of rolls for guiding the blank.

9. A machine for completely coating one surface of a blank with an adhesive, comprising a roll with separated collars having glue-applying peripheral faces, and a second roll having separated collars projecting into the spaces between said first named collars 90 and also having glue-applying peripheral faces, said second roll operating when said rolls are rotating to guide the blank from the first named roll, and fixed means beyond said second named roll for guiding the blank 95 therefrom.

10. A machine for coating a surface of a blank with an adhesive, comprising a roll with separated collars having glue-applying peripheral faces, a second roll having separated collars with glue-applying peripheral faces, the collars of said second roll projecting into the spaces between said first named collars, said second roll operating when said rolls are rotated to guide the blank from the first named roll, and means 100 coöperating with said rolls for engaging the side of the blank remote from said rolls to assist in holding the blank in contact with said rolls.

11. A machine for coating a surface of a blank with an adhesive, comprising a roll with separated collars having glue-applying peripheral faces, a second roll having separated collars with glue-applying peripheral faces, the collars of said second roll projecting into the spaces between said first named collars, said second roll operating when said rolls are rotated to guide the blank from the first named roll, and a roller having its 110 peripheral face adjacent but out of contact with said collars coöperating with said rolls for engaging the side of the blank remote from said rolls to assist in holding the blank in contact with said rolls.

12. A machine for successively applying a plurality of thin coats of an adhesive to a blank, comprising a pair of rolls with

glue-applying peripheral faces with the peripheral faces of one roll out of alinement with and extending beyond the peripheral faces of the other roll for applying the first coat of the adhesive to the blank, and a second pair of rolls having separated glue-applying peripheral faces, the said peripheral faces of one of said second named rolls out of alinement with and extending beyond the peripheral faces of the other roll of said second pair, the peripheral faces of the second pair of rolls out of alinement with the peripheral faces of the first pair of rolls, and means for conveying a thin coat of the adhesive to both pairs of rolls.

13. A machine for successively applying a plurality of thin coats of an adhesive to a blank, comprising a pair of rolls with glue-applying peripheral faces with the peripheral faces of one roll out of alinement with and extending beyond the peripheral faces of the other roll for applying the first coat of the adhesive to the blank, and a second pair of rolls having separated glue-applying peripheral faces, the said peripheral faces of one of said second named rolls out of alinement with and extending beyond the peripheral faces of the other roll of said second pair, the peripheral faces of the second pair of rolls out of alinement with the peripheral faces of the first pair of rolls, means for conveying a thin coat of the adhesive to both pairs of rolls, and means coöperating with said rolls for engaging the blank on the outer side thereof to maintain the blank in contact with the said rolls.

14. A machine for coating one surface of a blank with an adhesive, comprising a distributer roll, a pair of glue-applying rolls with glue-applying peripheral faces, said pair of rolls tending by gravity toward contact with the peripheral face of said distributer roll and freely movable away from said distributer roll, and means for simultaneously adjusting said pair of rolls away from said distributer roll to adjust the relation of the peripheral faces thereof with respect to the peripheral face of said distributer roll.

15. A machine for coating one surface of a blank with an adhesive, comprising a frame, a distributer roll supported in said frame, a pair of rolls with glue applying peripheral faces, means for guiding said pair of rolls on said frame so that they are freely movable away from said distributer roll but tend by gravity to rest thereupon with the glue-applying peripheral faces of said pair of rolls tending to contact with the peripheral face of said distributer roll, and means for simultaneously adjusting said pair of rolls away from said distributer roll to adjust the relation of the peripheral

faces thereof with respect to the peripheral face of said distributer roll.

16. A machine for successively applying a plurality of thin coats of an adhesive to a blank, comprising a distributer roll, a pair of rolls with glue-applying peripheral faces with the peripheral faces of one roll out of alinement with and extending beyond the peripheral faces of the other roll for applying the first coat of the adhesive to the blank, a second pair of rolls having separated glue-applying peripheral faces with said peripheral faces of one of said second named rolls out of alinement with and extending beyond the peripheral faces of the other roll of said second pair, the peripheral faces of the second pair of rolls out of alinement with the peripheral faces of the first pair of rolls, said pairs of rolls having their glue-applying faces lying adjacent to the peripheral face of said distributer roll, and means for adjustably supporting the glue-applying rolls to regulate nicely the relation of the glue-applying faces to the face of said distributer roll.

17. A machine for successively applying a plurality of thin coats of an adhesive to a blank, comprising a distributer roll, a pair of rolls with glue-applying peripheral faces with the peripheral faces of one roll out of alinement with and extending beyond the peripheral faces of the other roll for applying the first coat of the adhesive to the blank, a second pair of rolls having separated glue-applying peripheral faces with said peripheral faces of one of said second named rolls out of alinement with and extending beyond the peripheral faces of the other roll of said second pair, the peripheral faces of the second pair of rolls out of alinement with the peripheral faces of the first pair of rolls, said pairs of rolls having their glue-applying faces lying adjacent to the peripheral face of said distributer roll, and a guide and presser roller coöperating with the adjacent rolls of the pairs of rolls for guiding the blank from one pair of rolls to the other.

18. A machine for successively applying a plurality of thin coats of an adhesive to a blank, comprising a distributer roll, a pair of rolls with glue-applying peripheral faces with the peripheral faces of one roll out of alinement with and extending beyond the peripheral faces of the other roll for applying the first coat of the adhesive to the blank, a second pair of rolls having separated glue-applying peripheral faces with said peripheral faces of one of said second named rolls out of alinement with and extending beyond the peripheral faces of the other roll of said second pair, the peripheral faces of the second pair of rolls out of alinement with the peripheral faces of the first pair of rolls, said pairs of rolls having their

- glue-applying faces lying adjacent to the peripheral face of said distributor roll, a guide and presser roller coöoperating with the adjacent rolls of the pairs of rolls for guiding the blank from one pair of rolls to the other, and guide rollers corresponding to each pair of rolls for guiding the blank between the rolls of each pair of rolls.
19. A machine for successively applying a plurality of thin coats of an adhesive to a blank, comprising a frame, a distributor roll supported in said frame, a plurality of pairs of rolls having separated glue-applying peripheral faces lying adjacent to the peripheral face of said distributor roll, the glue-applying faces of one roll of each pair being out of alinement with and extending beyond the peripheral faces of the other roll of that pair, and means for adjusting the glue-applying rolls toward and from the distributor roll.
20. A machine for successively applying a plurality of thin coats of an adhesive to a blank, comprising a frame, a distributor roll supported in said frame, a plurality of pairs of rolls having separated glue-applying peripheral faces lying adjacent to the peripheral face of said distributor roll, the glue-applying faces of one roll of each pair being out of alinement with and extending beyond the peripheral faces of the other roll of that pair, said glue-applying rolls having shafts supported in said frame so that the glue-applying rolls are freely movable away from the distributor roll, and a member mounted to rotate on the axis of the distributor roll for simultaneously adjusting the glue-applying rolls toward or from the distributor roll.
21. A machine for coating one surface of a blank with an adhesive, comprising a roll having a glue-applying periphery, means for supporting a pack of blanks to be coated in vertical position and on edge below said roll and with the upper edge of the foremost sheet lying adjacent the periphery of said roll, and means for reciprocating the pack to bring the foremost blank of the pack into contact with said roll to enable said roll to separate the foremost blank from the pack and advance the same into the machine.
22. A machine for coating one surface of a blank with an adhesive, comprising a roll having spaced glue-applying faces, means for supporting a pack of blanks to be coated in vertical position and on edge below said roll and with the upper edge of the foremost blank lying adjacent the periphery of said roll, means for bringing the foremost blank of the pack into contact with said roll to enable said roll to separate the foremost blank from the pack and advance the same into the machine and other glue-applying rolls having spaced glue-applying faces co-operating with said first named roll to complete the application of the adhesive to the blank.
23. A machine for coating one surface of a blank with an adhesive, comprising a frame, a distributor roll supported in said frame, said frame having open sockets extending toward said distributor roll, a plurality of glue-applying rolls having shafts received in said sockets to guide said rolls toward or away from said distributor roll, and a cam rotatably mounted on the axis of said distributor roll, said cam having a plurality of cam edges engaging the shafts of said glue-applying rolls for adjusting the relation of the glue-applying faces thereof to the face of said distributor roll.
24. A machine for coating one surface of a blank with an adhesive, comprising a frame, a distributor roll supported in said frame, a pair of glue-applying rolls having shafts guided in said frame and freely movable toward and away from said distributor roll, said pair of glue-applying rolls having separated glue-applying peripheral faces, the glue-applying faces of one of the rolls of the pair out of alinement with and extending beyond the glue-applying faces of the other roll of that pair, a second pair of glue-applying rolls having shafts guided in said frame and freely movable toward and away from said distributor roll, the rolls of said second named pair having glue-applying peripheral faces, the faces of one of said rolls out of alinement with and extending beyond the glue-applying faces of the other roll of that pair, means for guiding the blank as it passes said glue-applying rolls, and means for adjusting the relation of said glue-applying rolls to said distributor roll.
25. A machine for applying a coating to a blank, comprising a pair of rolls, each of said rolls having separated faces, the faces of one of said rolls being out of alinement with the faces of the other roll, means for guiding the blank past said rolls to apply a coating thereto from said faces, and means beyond said rolls for again applying a coating to the blank.
26. A machine for applying a coating to a blank, comprising a pair of rolls, each of said rolls having separated faces, the faces of one of said rolls being out of alinement with the faces of the other roll, means for guiding the blank past said rolls to apply a coating thereto from said faces, and means beyond said rolls for again applying a coating to the blank.
27. A machine for applying a coating to a blank, comprising a pair of rolls, each of said rolls having separated faces, the faces of one of said rolls being out of alinement with the faces of the other roll.

with the faces of the other roll, means for guiding a blank past said rolls to apply a coating thereto from said faces, and means beyond said rolls for again applying a coating to the blank, said last named means including a second pair of rolls, each of said second pair of rolls having faces out of alinement with the faces of the other of said second pair of rolls, the faces of said second pair of rolls being out of alinement with the faces of said first named pair of rolls.

28. In a gluing machine, a pair of rolls each having spaced glue-applying faces, the faces of one roll operably disposed between the faces of the other roll and means for coating the glue-applying faces of both of said rolls with glue.

29. In a gluing machine, a pair of rolls for applying glue to the blank, a second pair of rolls for applying glue to the blank, each of said rolls having spaced glue-applying faces, said rolls being arranged so that the glue-applying faces of each roll lie be-

tween the glue-applying faces of its adjacent roll.

30. In a gluing machine, in combination, a frame, coating means mounted in said frame for applying a coating to a blank, a conveyer frame pivotally mounted on said first named frame, an endless conveyer to receive the coated blanks from the coating means mounted on said conveyer frame, an endless belt mounted on said conveyer frame disposed adjacent said conveyer to prevent the coated blanks from curling up at their edges, a gear wheel on said first named frame and a gear wheel on said conveyer frame meshing therewith for driving said conveyer and said belt.

In testimony whereof we have hereunto set our hands in presence of two subscribing witnesses.

JAMES D. REIFSNYDER.
HARRY B. SMITH.
